Filed Apr. 7, 1961, Ser. No. 101,386

22 Claims. (Cl. 5—67)

This invention relates to beds, and is particularly related to a bed having an articulated bed frame comprising a head section, a seat section pivoted to the bed section, and a foot section pivoted to the seat section.

An object of this invention is to provide in a bed, an improved bed frame that could be converted from a flat horizontal position to a position in which the head and back support section would be elevated for viewing television or reading and at the same time the knees would be elevated to a very comfortable position, in which the bed frame would support a mattress and means to lock the bed frame in an infinite number of positions from completely flat to an almost upright position of the head section.

Bed with bed frames having head, seat and foot sections that could be moved from flat to various inclined positions have been known, but such devices as heretofore made were operated either by external sources of power which are expensive, or such devices had to be operated either by another person or required the occupant of the bed to get out of bed to adjust them which is very inconvenient.

It is hence another object of this invention to provide a bed construction of the character described, so constructed that the positions of the sections of the bed frame can be changed solely by the occupant unlocking the lock and shifting his weight, thereby making the bed less expensive and easy and convenient to operate.

Still another object of this invention is to provide a bed comprising a bed base, a lever pivoted to the bed base for angular movement relative thereto, and a bed frame comprising a head section, a seat section pivoted to the head section, and a foot section pivoted to the seat section, said bed frame being connected to the lever for movement of its sections to various angular positions relative to the others and relative to said lever, whereby said bed frame in each of the various relative angular positions of its sections, can be moved as a whole relative to the bed base, by moving the lever angularly relative to said head base.

Another object of this invention is to provide, in a bed of the character described, a bed frame for a mattress, said bed frame having a head section and a seat section, said sections being movable from co-aligned positions to angular positions of less than 180°, one relative to the other, and means at the pivot corner for said sections, to support the portion of the mattress which overlies the pivot, and which cannot fit into the corner or apex of the angle between said sections, whereby the mattress on the bed frame (which bends to conform to the angles of the sections of the bed frame) is better supported and hence adds to the comfort of the user.

Still another object of this invention is to provide in a bed of the character described, means to lock the lever to the bed base, said means being releasable manually, and separate means to lock the bed frame sections against movement relative to each other and to the lever, said latter lock means also being releasable manually and independently of the lever lock means, the construction being such, furthermore, that back lock means are normally in locking condition and are unlocked only while the operator is actuating them, and both said lock means reverting to locked condition when the operator stops actuating them.

2

Still another object of this invention is to provide a bed of the character described having means to raise the seat and foot sections to a position higher than the back section, and means to move the bed frame to a position where the head, seat and foot sections are horizontally aligned, means being further provided to hold the outer end of the head section against movement below a predetermined height.

Yet another object of this invention is to provide in a bed of the character described, highly improved means to prevent side sway or movement of the bed frame in the various positions thereof.

A still further object of this invention is to provide in a bed of the character described, highly improved locks for the lever and for the bed sections, said locks including push buttons, and said locks being normally locked, and being released only while the push buttons are depressed.

Yet a further object of this invention is to provide a strong and durable bed of the character described, which shall be relatively inexpensive to manufacture, easy to manipulate, which shall be smooth and positive in operation, and yet practical and efficient to a high degree in use.

Other objects of this invention will in part be obvious and in part hereinafter pointed out.

25 The invention accordingly consists in the features of construction, combinations of elements, and arrangement of parts, which will be exemplified in the construction hereinafter described and of which the scope of invention will be indicated in the following claims.

30 In the accompanying drawings in which is shown an illustrative embodiment of this invention,

FIG. 1 is a top plan view of one side of a bed embodying the invention, with the bed frame in horizontal position;

35 FIG. 2 is a cross-sectional view of the bed shown in FIG. 1 taken on line 2—2 of FIG. 1.

FIG. 3 is a view of the bed similar to FIG. 2, with the lever in normal position, but with the bed frame sections in angular positions;

40 FIG. 4 is a view of the bed similar to FIG. 2, with both the lever and the frame sections in angular positions;

FIG. 5 is a view of the bed similar to FIG. 2, with the lever in angular position and the head section contacting a stop below which its outer end cannot move;

45 FIG. 6 is a cross-sectional view taken on line 6—6 of FIG. 2;

FIG. 7 is a cross-sectional view taken on line 7—7 of FIG. 2;

50 FIG. 8 is a cross-sectional view taken on line 8—8 of FIG. 2;

FIG. 9 is a cross-sectional view taken on line 9—9 of FIG. 10 is a cross-sectional view taken on line 10—10 of FIG. 8;

FIG. 11 is a cross-sectional view taken on line 11—11 of FIG. 2;

FIG. 12 is a cross-sectional view taken on line 12—12 of FIG. 8;

FIG. 13 is a cross-sectional view taken on line 13—13 of FIG. 2;

60 FIG. 14 is a cross-sectional view taken on line 14—14 of FIG. 2;

FIG. 15 is a cross-sectional view taken on line 15—15 of FIG. 2; and

65 FIG. 16 is an enlarged, cross-sectional view taken on line 16—16 of FIG. 2.

Referring now in detail to the drawing, 10 designates a bed embodying the invention. Bed 10 comprises a bed base 11. The base 11 comprises a pair of parallel, horizontal, coextensive, symmetrical side members 12 of angular cross section, each having a vertical upwardly extending flange 13 at the lower end of which is a horizontal

inwardly extending flange 14. Said side members 12 are supported in end legs 15 and may be interconnected by usual suitable cross-members, not shown.

A head rest board 16 may be fixed to the head ends of the bed base, extending upwardly from the side members and suitably fixed thereto. At the inside of the head rest 16 is fixed a horizontal transverse angle shaped member 17 having an inwardly extending flange 18 and a downwardly extending flange 19, for the purpose hereinafter appearing. Member 17 is spaced above the side members 12, as shown in the drawings.

Fixed to opposed portions of the inner sides of the flanges 13 of side members 12, somewhat closer to the head ends than foot ends of said members, as by rivets 20, are brackets 21, 21a (FIGS. 2, 6, 8).

Bracket 21 has a lower portion 23 contacting the inner side of flange 12, an intermediate outwardly bent portion 24 overlying the upper edge of said flange, and an upper portion 25 disposed in a plane outside of said flange. Portion 25 has an opening 26 with opposed flat edges 27 (FIG. 10), and round opposed edges 28 alternating with edges 27, non-rotatably fitted into opening 26 is a reduced end hub 29 of a lock housing 30, having surfaces 27a, 28a contacting said surfaces 27, 28. Lock housing 30 has an axial through opening 31 through which passes one end of a rod 32. Extending from the hub 29 is an enlarged intermediate portion 33 having an outer circular surface 34. Extending from the intermediate portion 33 is button or flange 35 of greater diameter. Intermediate portion 33 is formed with three equiangularly spaced, radial drilled holes 36 having inner frustoconical portions 37 extending to the inner surface 31 (formed by the base of the drill point) thereby providing seats for balls 38 dropped into the holes. The balls project through the holes 37a in the seats 37 to contact the outer surface of rod 32.

The bracket 21a is symmetrically disposed relative to bracket 21 and is similar thereto except that instead of being formed with opening 26 as shown in FIG. 10, it is formed with a round opening 40, in which the other end of rod 32 is journaled. Said rod 32 has flattened ends 41 received in similar shaped holes 42 in levers 43. Said ends 41 are riveted over and levers 43 are rotatable with rod 32.

The levers 43 are similar and aligned. Rod 32 is the axis of rotation for said levers. Each lever has a forwardly extending arm 44, the major portion of which is located in a plane outside of the flange of flange 13. The front end of each lever portion 44 is offset outwardly, as shown in FIGS. 1 and 7. Extending rearwardly of the pivot points of levers 43 are straight portions 46 in the plane of portion 44. Extending from each portion 46 is an upwardly bent portion 47 from which extends an upwardly inclined arm 48. At the upper end of arm 48 is an outwardly offset end portion 49 in the plane of portion 45. As shown in FIGS. 2 and 3, arms 44 and portions 46 of the levers 43 are parallel to side members 12 and located thereabove, in one position of said levers.

Levers 43 may be rotated in clockwise directions from the position of FIGS. 2 and 3 to the positions of FIGS. 4 and 5.

Rotatably mounted on the intermediate portion 33 of lock housing 30 is a lock actuating arm 50. Arm 50 narrows forwardly. At its rear end it has an inwardly offset portions 50a formed with an opening 51 receiving said intermediate portion 33 and surrounding surface 34 and confining the balls 38 to their openings or drilled holes 36. Opening 51 has three similar segments 52 of 120° each. Each segment is of greater radius at the ends than in the middle. The middle of the segments 52 substantially contact surface 34 of intermediate portion 33. When the meeting ends of the segments 52 are over the drilled holes 36, the balls 38 may move radially outwardly and are loose on the rod 32, and said rod together with levers 43 may rotate. When said arm 50 is

rotated in a counter-clockwise direction, in the manner hereinafter explained, to its normal position, the middle portions of segments 52 are over the drilled holes 36, and the balls 38 are pressed radially inwardly to project through openings 37a in the ball seals 37, to grip the rod 32 and prevent the rod from rotating, and hence also keep the levers 43 from rotating.

Means is provided to normally retain the actuating arm 50 in position for locking levers 43. To this end, there is fixed to flange 13 of the side member which carries bracket 21, as by screws or rivets 55, an upstanding bracket 56 having at its upper end, an inwardly offset finger 57 formed with an opening 58 receiving a hub 59 fixed thereto and formed with an axial through opening 60 for the purpose hereinafter appearing. Finger 57 overlies the small forward end of actuating arm 50. Said arm at its small end, has an upstanding finger 61 aligned with hub 59. Interposed between finger 57 and arm 50 is a coil compression spring 62. Its upper end receives the lower end of hub 59. Its lower end receives finger 61. Thus spring 62 presses down on arm 50 to retain the lock in locked condition. It is only when the arm 50 is rotated upwardly against the pressure of spring 62, in the manner to be described hereinafter, that the lock is released, and the levers 43 released for rotation.

Means is provided to control rotation of levers 43 in a clockwise direction looking at the drawing, to raise the forward ends 45 of the levers. To this end, there is fixed to the inner sides of portion 44 of each lever 43, a bracket 65 having a rearwardly extending tongue 66 riveted to said portion as at 67. Extending inwardly from the forward end of tongue 66 is an intermediate offset 68 from which extends forwardly, a tongue 69 parallel to and spaced from said portions 44 and terminating close to portion 45 of the lever. Pivoted to tongue 69, as by pivot pin 70, is a link 71. Said link 71 has one end 72 received between tongue 69 and lever portion 44. Beyond tongue 69, said link 71 has an inwardly extending offset 72 from which extends the outer end 73 of the link, in the plane of said tongue 69. Tongue 69 is in the plane of flange 13 of side member 12, as seen in FIG. 7. Pivoted to the outer end 72 of link 71, as by transverse pivot pin 74, are a pair of parallel links 75, 76 disposed on opposite sides of link end 73. The lower ends of links 75, 76 are on opposite ends of flange 13 and are pivoted thereto by a common transverse pivot pin 77 located only slightly forwardly of pivot pin 70 when the lever 43 is in its down position. It will now be understood that levers 43 may be swung up, when the ball lock is released, from the down position of FIG. 2 to the upmost position of FIGS. 4 and 5. The links 75, 76 being received on opposite sides of link 73, and portion 72 of said link, being received between tongue 69 and lever portion 44, serves to stabilize the structure against side-sway.

When levers 43 swing back, the bent or curved portions 47 thereof dip below the upper edges of flanges 13 of side members 12, as seen in FIGS. 4 and 5.

Supported on and by the levers 43 is a bed frame 80 comprising a head or end section 81, a middle or seat section 82 hinged to the forward end of the head section, and a foot or leg section 83 hinged to the forward end of the seat section. The head section 81 comprises a transverse angle shaped bar 84 having a top forwardly extending flange 85 from the rear of which extends downwardly a flange 86. Fixed to the ends of cross-bar 84 are parallel side bars 87, likewise of angle shaped cross-section and having top inwardly extending flanges 88 and outer, downwardly extending flanges 89. Flange 89 of the side-bars 87 are interconnected by a cross-brace of tubular stock having flattened ends 91 riveted as at 92 to said flanges. The cross-braces 90 may be downwardly offset centrally as at 93 in FIG. 6, which illustrates another cross-brace 90 to be described hereinafter.

In the horizontal position of the bed frame, with head seat and front sections co-planar, the bed frame is spaced

above the lower edge of flange 86 of the base, and cross-bar 84 contacts the upper side of flange 18 of stop bar 17 as shown in FIG. 2 of the drawing.

Flange 88 each side bar 87 terminates, at its forward end, short of flange 89 of said bar, as shown in FIG. 1.

The upper ends of portions 49 of the levers 43 contact the inner sides of flanges 89 and are pivoted thereto by pivot pins 95.

The seat section 82 comprises parallel side bars 96 of angle cross-section, each comprising a top, inwardly extending flange 97, and an outer, downwardly extending flange 98. At the far side of the bed, the forward end of flange 89 is pivoted, as by pin 99 to the rear end of adjacent flange 98. At the opposite side of the bed the flanges 89 and 98 are interpivoted by a pin (not shown) coaxial with pin 99 but shorter than said pin. Flanges 97 terminate at their rear ends short of the pivots 99 (FIG. 1).

The bars 96 are interconnected by a pair of spaced cross-braces 90 similar to the cross-brace 90 described above, and located adjacent the outer ends of flanges 97.

Foot section 83 comprises a pair of side-bars 100 interconnected by a front cross-bar 101, all of angle shaped cross-section. Bars 100 have top horizontal flanges 102 and downwardly extending vertical flanges 103. Cross bar 101 has a top flange 105 and a vertical downwardly extending flange 106.

The rear end of flanges 98 are offset inwardly as at 98a to be located at the insides of flanges 89, as shown in FIG. 11. The forward ends of flanges 103 are in planes at the outsides of rear ends of flanges 98 as shown in FIG. 15.

Fixed to the inside of each flange 98, adjacent its forward end, is a bar 110 having an inwardly offset portion 111 spaced from the portion of flange 98 which extends beyond flange 97. Fixed to the inside of each flange 103 is a bar 112 having an inwardly offset portion 113 extending rearwardly beyond flange 102 and spaced from flange 103. Flange 98 is received between flanges 103, 113. Flange 113 is received between flanges 98, 111. Flanges 103, 98, 113, 111 are pivoted by pivot pin 115. Thus, a pivotal connection and stabilizer is provided for the seat and foot section, to prevent side sway of said sections.

Means is provided to connect the foot section to the levers 43. To this end, the forward ends of levers 43 are connected to the side bars 100 of the foot section by pairs of spaced links 120, 121. Each link 120 is pivoted at its lower end, to portion 45 of lever 43 by pivot pin 123 and at its upper end by pivot pin 124 to flange 103 of side bar 102. Each link 121 is pivoted at its lower end to the forward end of lever 43 by pivot 125 and at its upper end to said flange 103 by pivot pin 126. The links 120 are of greater length than links 121, and more inclined to the horizontal when the bed frame is in the position of FIG. 2. With such construction, as the foot section 83 is pulled back from position of FIG. 2, to the position of FIG. 3, said foot section will incline downwardly and forwardly as shown in FIG. 3.

When the levers 43 are in normal position, with arms 44 horizontal, and with head and seat sections of the bed frame horizontal, the foot section will also be held in horizontal position by links 120, 121. When the foot section is horizontal, the links 120, 121 are inclined forwardly and upwardly. Pivot points 123, 125 are somewhat further apart than pivot points 124, 126.

Means is provided to releasably lock bed frame sections 81, 82, 83 against relative movement in any relative angular positions thereof. To this end there is rotatably mounted on pivot pin 99 (at the right side of the bed or the same side that has the releasable lock shown in FIGS. 8, 10, 12) a lock housing 130 similar in shape to lock housing 30. Said lock housing 130 has a through opening 131, through which pin 99 passes.

Pin 99 has flats to engage in an opening with corre-

sponding flats in flange 89 so that pin 99 will not rotate relative to said flange. Lock housing 130 has an outer hub 130a with flats received in a corresponding hole 132 with flats, in portion 98a of flange 98. Lock housing 130 has an intermediate portion 133 of circular shape formed with three equiangularly spaced, radial, drilled holes 134 having annular seats 135 at their inner ends providing holes 136. Balls 137 in the radial holes 134 seat on the seats 133 and project through holes 136 to contact the pin 99. An enlarged inner hub or button 138 is provided at the inner side of lock housing 130. Rotatably mounted on intermediate hub 133 is the rear end 140 of a lock arm 141. Said rear end 140 has a hole 142 similar to hole 51. It also presents three equal segmental edge portions of less diameter at the middle and gradually increasing in diameter toward its ends. When lock arm 141 is in its up position, the mid-portions of the segments are over the drilled holes to press the balls radially inwardly into gripping position relative to the pin 99, thereby preventing rotation of sections 81, 82 one relative to the other. Actuating arm 141 narrows toward its forward end. It is formed, in its upper edge with a notch 144 to accommodate the flat end 91 of one of the brace-bars 90. Upon rotating said arm 141 downwardly in a counter-clockwise direction, the ends of the segments of opening 142 are brought over the drilled holes 134 allowing the balls 137 to move radially outwardly, thereby releasing pin 99 and permitting rotation of the bed sections.

Means is provided to normally retain the actuating arm 141 in up or locking position. To this end, a bracket 150 is fixed to the inside of flange 98 of side bar 96 adjacent the forward end of actuating arm 141. Said bracket extends down below flange 98 and has an inwardly extending finger 151. A pin 152 is fixed to the finger 151 and projects upwardly therefrom. Said arm 141 is formed at its front end with a downwardly projecting lug 153 aligned with pin 152. A coil compression spring 155 is interposed between finger 151 and arm 141, said spring receiving said pin 152 at its lower end, and the lug 153 at its upper end.

Flange 97 is formed with a hole 156 directly above the narrow end of arm 141. A push button 157 has its upper end slidably extending through said hole. Said button has an enlarged base resting on the arm 141. The spring 155 normally presses arm 141 upwardly, to retain the lock housing in locking or pin gripping position. However, upon pushing the button 157 the arm 141 is depressed sufficiently to bring the lock housing to releasing position. The lock housing remains in releasing position only as long as the push button is manually depressed. This construction makes sure that the bed frame sections will not move accidentally one relative to the other unless and only while the push button 157 is being depressed.

Means is provided to release the lock housing 30 for the levers 43. To this end, there is pivoted to the inside of flange 98 on the same side of the bed as arm 50, as by pivot 160, a lever 161 having a rearwardly extending arm 162 lying beneath flange 98, and a forwardly extending downwardly inclined arm 163. Fixed to the inside of flange 98 is a bracket 164 having an inwardly offset finger 165 at its lower end formed with an opening in which is mounted a hub 166 formed with a through opening 167. A wire 168 has one end hooked through an opening 169 in arm 162 and passes through opening 167 in hub 166 and then passes down through opening 60 in hub 59, through coil spring 62 and is connected or hooked to arm 50 through an opening 50b therein. A flexible sleeve 170 receives the wire 168 and is interposed between hubs 166 and 59.

Flange 97 of side bar 96 has a hole 175 in which is slidably mounted a push button 176 similar to push button 157 and overlying arm 162 of lever 161 and contacting said arm. Upon pushing button 176, lever 161 is rotated in a clockwise direction (FIG. 5) to cause a pull on wire 168 upwardly to cause the wire to move through sleeve

170 to pull up arm 50 to rotate the lock housing bushing 30 to releasing position. Such movement compresses spring 62, so that as soon as the operator takes his finger off the push button 176, said spring will again pull down on the wire 168 to move the arm 50 back to normal locking position. 5

It will now be understood that with the levers 43 in their normal positions of FIGS. 2 and 3, button 176 may be depressed and the bed sections moved from the flat horizontal coplanar positions of FIG. 2, to the position of FIG. 3 or to any intermediate position between these two extremes. The bed sections can be locked in any of these positions by taking the finger off the push button 176. The person lying in the bed need merely press down forwardly of pivots 95 (after pushing button 176) and the head section will rotate about said pivots in a counterclockwise direction to cause the forward end of the head section to pull downwardly and rearwardly in the seat section, which, in turn, pulls back on the foot section to cause it to move under control of links 120, 121. The push buttons 157, 176 may be provided adjacent their upper ends with grooves receiving snap rings 157a, 176a to prevent the push buttons from falling out of their holes. 20

A mattress M may be placed on the bed frame.

Also, usual springs or wires may be provided to interconnect the bars of the bed frame sections to provide a platform support for the mattress. 25

The position of FIG. 3 may be considered a sitting up position. By keeping the bed frame sections locked, and releasing the levers 143, the bed frame as a whole may be swung back to the position of FIG. 4. This position may be called a T.V. position, that is, a position from which to watch television. 30

The position of FIG. 2 is for sleeping or lying down flat. 35

The position of FIG. 5 may be used for heart patients, since the foot section is raised above the head and back section. This may be called the fully reclined position. 40

It will now be understood that the levers may be pivotally moved with the bed frame sections locked in various relative inclined positions. 45

It will be observed that in many positions of the bed frame, the head section has an angular position relative to the seat section of less than 180°. In FIG. 4, this angle about 90°. The mattress M cannot fit into the corner space formed at the junction of the head and seat sections. Means is provided to support the mattress above such corner space, to give ample support to the mattress at such location. To this end there is pivoted to flanges 89 and 98 on each side of the bed, as by pivots 180, 181 spaced equi-distant from the pivot pin 99, downwardly and inwardly inclined links 182, 183, respectively. Supported on pivot pins 184, 185 at the lower ends of said links, at each side of the bed, is a cradle 190. Each cradle comprises a pair of similar symmetrical angular portions 191 located in a vertical plane interconnected by a top horizontal portion or flange 192. The flanges 192, as both sides of the bed are interconnected by a cross-brace 99, such as heretofore described. As the angle between the head section 81 and the seat section becomes smaller, the top flanges 192 cut across the cover formed by said sections, and the mattress M will be supported at said corner by said cradles 190, and the mattress will not wedge into such corner. The cradles 190 may be interconnected by wires or springs if desired. 50

Means is provided to limit upward rotation of levers 43, to prevent links 71, 75 from becoming coaligned, to thereby insure that said levers can be swung down again, and will not be locked in up position by said links. To this end, there is fixed to flanges 13 of one side member 12, a stop pin 200 which will contact an underedge of lever 43 as shown in FIGS. 4 and 5, when the levers 43 have reached their maximum desired upswing posi- 70

75 tions. In such position the stabilizing links 71, 75 are still at an angle one to the other.

It will thus be seen that there is provided an apparatus in which the several objects of this invention are achieved and which is well adapted to meet the conditions of practical use.

As possible embodiments might be made of the above invention, and as various changes might be made in the embodiment above set forth, it is to be understood that all matter herein set forth or shown in the accompanying drawings is to be interpreted as illustrative and not in a limiting sense.

It will be understood that the levers 43 may be rigidly fixed relative to the bed base, or be part of the base instead of being locked thereto, and the sections of the bed frame moved relative to the bed base, as shown in FIG. 3. The levers 43 may be eliminated and links 120, 121 pivoted directly to the bed base with arms 48 fixed to the bed base also.

I claim:

1. In combination, a bed base, a bed frame, comprising a head section, another section pivoted at its rear end to the forward end of said head section, means to support the bed frame on the base permitting said head section to move from a position coplanar with said other section to an angular position of less than 180° relative thereto, and means supported by said sections to support a portion of a mattress on the bed frame, and over the junction of said sections, above and across the corner formed at said junction when said sections are in angular position of less than 180° one relative to the other.

2. In combination, a bed base, a member pivoted to said base, a bed frame comprising a middle section and two ends sections, and means connecting the said bed frame sections to each other and to said pivoted member and dependent on angular movement of any one of said sections relative to said pivoted member to cause the other two of said bed frame sections to move in predetermined angular relationship to each other and to said pivoted member and to prevent angular movement of any one of said bed frame sections relative to said pivoted member without said accompanying predetermined angular movement of the other two bed frame sections relative to said pivoted member and relative to each other, said pivoted member being pivoted to said base mediate the ends thereof at substantial distances from said ends, providing arms extending to opposite sides of the pivot of said pivoted member to said base, said means including means connecting both said arms to said bed frame, and said pivoted member being swingable about its pivot to the base, in response to application of downward force to one or the other arms of the pivoted member.

3. The combination of claim 2, said first mentioned means comprising pivotal connections of the middle section to the end sections on pivots spaced from the pivotal connection of said pivoted member to said base, and movable relative to said pivoted member.

4. The combination of claim 3, and said first mentioned means further comprising a pivotal connection of one of said bed frame sections to said pivoted member on a pivot spaced from the pivotal connections of said middle section to said end sections, and spaced from the pivotal connection of said pivoted member to said base. 60

5. The combination of claim 4, said first mentioned means further comprising a plurality of links each pivotally connected to said pivoted member and each pivotally connected to a bed frame section other than the one pivoted to said pivoted member. 65

6. The combination of claim 4, in combination with means pivoted to one end section and to the middle section, to support a mattress on the bed frame, above the corner formed at the junction of said end and middle sections when said sections are in angular relation of less than 180°. 70

7. The combination of claim 4, in combination with means to releasably lock said bed frame sections in various angular positions of said sections against all movement of said sections one relative to another, and means independent of said first mentioned lock means, to releasably lock said pivoted member in various angular positions of said pivoted member against all movement of said pivoted member relative to said base.

8. The combination of claim 2, in combination with means to limit angular movement of said pivoted member relative to said base.

9. The combination of claim 8, said limiting means including stabilizing means to prevent side sway of said pivoted member relative to the bed base.

10. The combination of claim 2, in combination with stabilizer means to prevent side sway of one of said sections relative to another of said sections.

11. The combination of claim 2, said first mentioned means comprising a pivotal connection of one of said sections to said pivoted member on a pivot spaced from the pivotal connection of said pivoted member to said base, and said first mentioned including linkage means connecting said pivoted member with said bed frame, permitting floating movement of said other two bed frame sections as a whole relative to said pivoted member.

12. The combination of claim 2, and releasable means to lock said pivoted member to said base in various angular positions of said pivoted member to said base against all movement of said pivoted member relative to said base.

13. The combination of claim 2, and releasable means to lock said bed frame sections against all movement relative to each other and relative to said pivoted member, in various angular positions of said sections relative to each other and to said pivoted member.

14. The combination of claim 2, releasable means to lock said pivoted member to said base in various angular positions of said pivoted member against all movement relative to said base, and releasable means independent of said first mentioned lock means to lock said bed frame sections in various angular positions of said sections relative to each other, against all movement of said sections relative to each other and relative to said pivoted member.

15. The combination of claim 2, said first mentioned means comprising a pivotal connection of one of said sections to said pivoted member, and a pair of links each connecting said pivoted member with a bed frame section other than the one to which the pivoted member is pivoted.

16. The combination of claim 15, and said first mentioned means further comprising means to pivotally connect the ends of said middle section to said end sections on pivots movable relative to said pivoted member and spaced from the pivotal connection of said one of said bed frame sections to said pivoted member and spaced from the pivotal connection of said pivoted member to said base.

17. The combination of claim 16, in combination with means connected to said middle section with an end section to support a mattress on the bed frame, above a corner formed at the junction of said sections.

18. In combination, a bed frame, a lever pivoted medately the ends thereof, to said base and having oppositely extending arms, a bed frame comprising a middle section pivoted at the ends thereof to a pair of end sections, one end of the lever being pivoted to an intermediate portion of one end section, and a link pivoted at its ends to said other end section and to said other arm of said pivoted member, the pivotal connections of said middle section to the end sections being movable relative to said lever.

19. The combination of claim 18, and a second link longitudinally spaced from the first link and pivoted to said other arm of said lever and to said other end section.

20. The combination of claim 19, said links and lever being dimensioned to retain said sections in coplanar horizontal position in spaced relation above said base in one relative angular position of said sections and lever.

21. The combination of claim 20, and stop means on said base to engage the underside of one end of one of said end sections, in said coplanar position.

22. In combination, a bed base, a bed frame, a support means, said bed frame comprising a middle bed frame section and a pair of end bed frame sections, means to mount said bed frame sections on said support means for angular movement of said sections relative to each other and relative to said support means, said mount means including means dependent upon movement of any one of said bed frame sections relative to said support means, to cause predetermined relative angular movement of said other two bed frame sections, and means to movably mount said support means on said base for movement of said support means to various angular positions relative to the base, whereby to move said bed frame sections in any fixed position relative to each other and to said support means, angularly of the base, said mount means including means to permit floating movement of two of said sections as a whole relative to said support means, means to releasably fix said bed frame sections in various positions relative to said support, and means to fix said support means to said base in various positions of said support means relative to said base.
